UNITED STATES PATENT OFFICE.

LUIGI ROBIMARGA, OF MILAN, ITALY.

SOUND-REPRODUCING MACHINE.

Application filed October 3, 1924, Serial No. 741,442, and in Italy October 4, 1923.

This invention has reference to improvements in or connected with sound reproducing machines of the type comprising a plurality of record discs adapted for successive operation whereby a continuity of reproduction of a series of records may be obtained. The present invention has for its object to provide means for accurately determining and effecting the change from the one record disc to the succeeding disc. The invention consists of an improved sound reproducing machine of the kind hereinbefore referred to, comprising a plurality of record disc carrying tables, a continuously driven shaft, a pair of auxiliary shafts on either side thereof and axially in line therewith, each of said auxiliary shafts being geared to a disc carrying table, spring operated means for connecting alternately one or other of said auxiliary shafts to the driving shaft, means for determining the point at which the change is to be effected, and means for automatically effecting the said change. The invention further consists in the improved details of construction and in the device as a whole.

In the annexed drawing which serves to illustrate in a schematical manner by way of example a device for the change of discs:

Figure 1 is a top view of the machine with the record carrying disc tables removed for the sake of clearness; Figure 2 is a side elevation of the machine; and Figure 3 is a perspective view of the mechanism for effecting the automatic change over from one record disc to another.

As it may be seen from the drawing the machine comprises a foundation plate 1 wherein is mounted a small electric motor 2 which serves to drive the devices. The current enters the motor by a conduit 3 ending at the terminal 4 which by means of a pin 5 is reconnected with the feeding conduit.

The motor 2 drives a shaft 6 which carries a wheel which, by means of a chain 7, transmits the movement to a second chain wheel keyed on the driving shaft 8 of the device.

The shaft 8 is borne by two supports 9', 9" fastened upon the foundation plate or plate 10 of the device, and on each of its ends carries a disc 15', 15" provided at its periphery with a carrying spring pawl 16', 16". On the right and on the left in alignment with

the shaft 8 but separated and independent from it are the two shafts 13', 13" which are borne by supports 14', 14" on the foundation plate 10. These two shafts carry on their inner ends adjacent the outer ends of shaft 8, two discs 11', 11" arranged against discs 15'—15", each of the former being provided with a notch 12', 12", one end of the spring pawl 16', 16" being pressed against the periphery of the opposite disc 11', 11" by a spring 17', 17" acting on the other end.

On the shafts 13', 13" are also mounted the bevel gears 18', 18" which mesh with the pinions 19', 19" and set into rotation the shafts 20', 20" of the turn tables 46', 46" bearing the record discs not shown in the drawing.

The shafts 20', 20" carrying the record tables are preferably each provided with a worm wheel 21', which through a worm 22' drives a centrifugal governor 23'. If it is desired to employ at one time two similar records, in order to amplify the volume of sound, two record carrying tables may be connected by means of a belt 25", said belt being perforated to engage with pegs on the periphery of a drum 24" secured to the shaft 20.

For clearness sake and in order to avoid unnecessary duplication of parts in the drawing only the worm wheel 21' connected with the shaft 20 and controlling the governor 23' has been shown, the governor controlled by shaft 20" being omitted and conversely only the belt 25", which transmits motion to a second record carrying table connected with the shaft 20" is shown, the corresponding connection of shaft 20' being omitted. The shafts 13', 13" bear also the two cams 26', 26" the object of which will be explained later on and the two worm screws 27', 27" gearing with the worm wheels 28', 28" keyed on shafts 29', 29" respectively. Finally they bear at their ends the two dial or indicating discs 30', 30" which rotate causing their graduation to run under a fixed pointer 31', 31" for the purpose which will be explained afterwards.

Upon the shafts 29', 29" bearing the worm wheels 28', 28" are keyed two discs 32', 32" which can be fastened on the shafts themselves by tightening the nuts 33', 33" screwed on the ends of the shafts themselves.

Said discs have graduations 34', 34" along

their edge and notches 35', 35" wherein can snap the release teeth 36', 36" of the movable switching bolt.

Said bolt consists in a flat bar 37 with two little windows 38', 38" across which project the aforesaid release teeth 36', 36". These teeth are a part of two movable pieces 39', 39".

Opposite bar 37 which is stationary, and in a parallel line with it is mounted a second bar 41 which is shiftable longitudinally and guided by two fixed pins 42', 42" which project through two slots 43', 43" with which it is provided. Besides the movable bar 41 bears two teeth 45', 45" which when the bar moves either to the left or to the right, meet, the tail of one of the pawls 16', 16" raising its end which was lowered into the notch of the disk 15', 15" and thus disconnect the discs 11', 15' or 11", 15".

From the above the action of the machine will now be easily understood assuming that the performance begins with the right disc borne by the shaft 20" and the other parts of the machine are in the positions shown by the figures of the drawing.

Upon each record disc prepared for the reproduction with the machine according to the invention, is marked a number which shows the number of turns required to complete the reproduction of all the matter that is recorded in it.

The operator slackens the nut 33" and having thus released the disc 32" pushes the tooth 36 towards the left, which he can do by overcoming the resistance of the spring 40", till it leaves the notch 35", opposite which there is the zero of the graduation 34", thereupon he turns the disc 32" sufficiently to bring the number marked on the record disc in front of the tooth 36" which runs along the periphery of the disc 32". During this movement the tooth 45" passes under the tail of the pawl 16' keeping it disengaged and the discs 11', 15' disconnected while the pawl 16" being free from tooth 45" its arm has fallen opposite the tooth 12" and connects together the discs 11", 15".

As soon as the movement has begun, when the record disc borne by the shaft 20" has accomplished the number of turns marked, the notch 35" arrives under the tooth 36" which falls therein.

In this movement the bar 41 is shifted to the right, the tooth 45" takes such position that it may be met by the tail of the pawl 16" when upon turning the disc 15" the said pawl arrives opposite bar 41 and at the same time the tooth 45" raises the tail of the pawl 16' whose free end falling against the tooth 12' establishes the connection of the two discs 11', 15' and thus begins the movement of the record disc borne by the shaft 20'. During the working of the first disc the operator had put into its place the second disc upon the

record carrying plate of the shaft 20' and turned the indicating disc 32' so far against the tooth 35' has come the number of the graduation 34' corresponding to the number of turns to be performed by the second disc. While the second disc is in operation the operator places the third disc and so forth.

When the sound reproducing machine should operate in connection with a cinematographic projection machine, with which it must move in synchronism, are utilized the two cams 26', 26" each one of which, at each turn of the shaft on which it is mounted closes for a certain interval the contact 44', 44" arranged on a circuit which operates a device for the automatic adjusting of the synchronism, a device which it is not necessary to describe here as it does not form a part of this invention.

In case of breakage of the film and stoppage of the machine, the hands 31' or 31" will show on the corresponding indicating disc 30' or 30" the exact point at which the sound repetition has reached and therefore the number of the picture with which the projection of the film must be resumed, because the pictures on the film are progressively numbered and to each turn of the sound recording disc corresponds always to the same number of pictures.

Claims:

1. In a sound reproducing machine of the kind referred to, comprising a continuously driven main shaft, two auxiliary shafts axially in line therewith, a disc carrying table, connected with each auxiliary shaft, couplings capable of being released and designed to alternately connect one or other of the two auxiliary shafts with the main shaft, and means for automatically actuating the coupling of the continuously driven main shaft with the auxiliary shafts, said means comprising a pair of control discs graduated in terms of the time length of the reproduction recorded in the discs and provided with notches, two shafts upon each of which is keyed one of the said control discs and each of which is connected to one of the auxiliary shafts, movable members, and springs controlling the movable members and co-operating with the said notches for actuating the automatic coupling and release of one of the auxiliary shafts with the main shaft at the same time at which is actuated the release and the coupling, respectively, of the second auxiliary shaft with the same main shaft.

2. Sound reproducing machines according to claim 1 having means for automatically performing the coupling of one of the auxiliary shafts with the main shaft at the same time at which is released the coupling which couples the other shaft, the said means including control discs provided with notches, the combination with the control discs of movable members consisting of a couple of

bars having angular portions adapted to enter the said notches, antagonistic springs acting upon said bars and causing them to enter the notches, and a rod sliding in two opposite 5 directions and acting upon the means for coupling the main shaft with the two auxiliary shafts, the said sliding rod being connected with the said bars and operated by

them in such a way as to establish the connection of the main shaft with one of the 10 auxiliary shafts at the same time at which the connection is released with the other one.

In testimony whereof I have affixed my signature September, 1924.

LUIGI ROBIMARGA.
